ATTORNEY

UNITED STATES PATENT OFFICE.

WILLIAM C. BURNS, OF ALBANY, OREGON.

CUBOID-SUPPORT SHOE.

Application filed September 7, 1921. Serial No. 498,899.

To all whom it may concern:

Be it known that I, WILLIAM C. BURNS, a citizen of the United States, residing at Albany, in the county of Linn and State of Oregon, have invented new and useful Improvements in Cuboid-Support Shoes, of which the following is a specification.

My present invention has reference to improvements in the manufacture of shoes.

10 In carrying out my invention, it is my purpose to produce, in the course of manufacture, a shoe in which the insole thereof is arched, thickened or reinforced at the shank on which the arch of the foot rests, said portion being of a shape, construction and nature to provide an effective rest for the said arch portion of the foot and to particularly provide a brace for the cuboid bone to support the same in a manner which increases 20 the strength of the muscles of the foot without the cramping of the parts thereof, and consequently permitting a free circulation of blood through all of the parts of the foot.

It is also my aim to produce a shoe in 25 which the cost of manufacture will be materially reduced and which is provided with integral means for effectively supporting the arch of the foot and particularly supporting and bracing the cuboid bone thereof to prevent the disassociation of such bone from 30 the remaining bones of the foot, and as a consequence produce a shoe which may be worn with perfect comfort by the user and in which the wearing thereof will materially 35 strengthen the muscles of the foot, the improvement particularly bracing the cuboid bone.

It is a still further object to produce a shoe in which the insole thereof is of such 40 nature and construction as to provide an effective brace for the arch portion of the foot and particularly a support for the cuboid bone which shall be of a nature and construction as to eliminate foot troubles, such 45 as the falling of the arch bones of the foot and which is also of a nature and construction as to afford the same support as were the wearer traveling barefooted through soft earth.

50 The foregoing, and other objects which will appear as the nature of the invention is better understood, may be accomplished by a construction, combination and operative association of parts, such as is disclosed by 55 the drawings which accompany and which form part of this specification.

In the drawings:

Figure 1 is a side elevation of a shoe constructed in accordance with this invention, parts being broken away and parts being in 60 elevation.

Figure 2 is a bottom plan view of the insole portion of the shoe.

Figure 3 is a sectional view on the line 3—3 of Figure 2. 65

Figure 4 is a perspective view of the substantially rigid member employed.

Figure 5 is a similar view of the heel cushion which may be employed.

Figure 6 is a plan view of the regulation 70 Army shoe sole or last, and indicating by the dotted lines the existing differences between applicant's construction thereover.

75 All the shoe makers that have designed or built shoes up to this date have built these shoes with the sole purpose of fitting the inside arch of the foot and if these shoes carried any weight at all under the instep they carried it against the cords and the circulations and this weight being carried under 80 the inside part of the foot acted as a leverage to tip the foot over in the shoe causing the foot to crowd in the shoe bringing pressure to bear on the toes causing corns, (hard and soft) while the strongest muscles of the foot 85 extended out or hung out over the outside edge of the curved insole, and these muscles deteriorated like any muscles that are not in use. They become in a weakened condition and these are the muscles that every 90 person depends upon to hold these twenty-six bones in their natural position. As these muscles become in a weakened condition, the weight of the body pressed these bones down out of their natural position, 95 interfering with the circulation, causing the weight to be carried against the cords, first symptoms—feet getting tired quickly and then the cords begin to ache in the legs causing cramps in the feet, and the person begins 100 to think that they have rheumatics in feet and legs when it is just the muscles weakening in the feet on account of the shoes were not constructed to carry weight on these muscles.

105 My invention will now describe a shoe built with the intention and sole purpose of carrying the weight under the cuboid bone and the muscles that hold the bones of the foot in their natural place. Instead of building the shoe to fit the inside arch of the 110 foot, my invention describes a shoe built for the purpose of fitting the outside part of

the foot from the base of the small toe to and including the calcaneum, the outside point of this bone. In order to build a shoe that will fit the outside part of the foot, the construction of the ordinary last is changed by adding enough to the last to cause a straight edge to extend from the base of the little toe to the extreme outside edge of the heel, that is adding to the last, from a quarter to a half an inch, and the same amount is deducted from the last by taking the same amount off the opposite side of the last extending from the ball of the foot to the extreme back part of the heel of the last.

15 Referring now to the drawings in detail, the numeral 1 designates generally a shoe of the ordinary construction. The sole 2, in my construction is arched at the shank thereof in the usual manner, but the said 20 arched portion is flat and is therefore of a width substantially greater than that of the ordinary construction. This also is true with respect to the insole 3, the said soles 2 and 3 being stitched, in the usual manner, 25 to the welt that secures the upper to the soles. To provide for the welt the insole has its edges grooved and channeled in the usual manner, and in the present construction, the insole, at the shank thereof between 30 the inner walls of the referred to grooves is channeled longitudinally to provide therein a pocket for a cuboid reinforcing element 4. The insole 3 has its outer edge parallel with the longitudinal axis of the heel and 35 the member 4 is arranged in a position to carry more weight under the cuboid bone than under the arch of the foot. The element 4 is arched longitudinally, the said member 4, however, being gradually decreased in thickness from one of its edges to 40 its opposite edge. This provides an elevated portion which is disposed directly below the cuboid bone of the foot and as a consequence pressure of this bone on the support will be materially greater than the pressure 45 received thereon from the scaphoid, and inner, middle and outer cuneiform bones. The result is that the cuboid bone being thus materially reinforced effectively holds the 50 remaining bones in proper position regardless of unevenness in the path traveled by the wearer of the shoe. From experience, I have found that when the cuboid bone is properly supported, the muscles of the foot 55 are materially strengthened, and by producing a shoe with the widened shank portion in which the reinforcement 4 is arranged, the foot is supported without liability of cramping so that the circulation of

blood through the foot is not interfered with. The outer edge of the sole is cut straight from the portion thereof on which the base of the little toe of the foot is supported to the extreme outside point of the heel. This provides ample room for the arch portion of the foot of the wearer, preventing the crowding and sliding of the foot in the shoe and the production of corns and callouses which are common with the ordinary construction of shoes. The foot is held substantially level on the insole of the shoe and is supported in a manner substantially similar to a barefooted person traveling over soft ground.

In order that the insert which provides the cuboid reinforcing element 4, will properly accommodate itself to the foot of the wearer, the same, from the edge thereof nearest the heel portion of the shoe is gradually and gracefully concaved from the corners 80 thereof inwardly, as clearly disclosed by the drawings. Thus, when the element 4 is received between the soles 2 and 3, the insole 3, at the portion thereof disposed directly opposite the said end of the insert will adapt 85 itself to the shape of the insert, and, as stated, will thus avoid any liability of injury to the foot of the wearer.

A heel pad 5 is inserted in the heel portion of the shoe until the wearer becomes accustomed to the wearing of the shoe, the same being arranged in the shoe in the manufacture thereof and removed when the wearer becomes accustomed to the shoe, and it is thought that the foregoing description, when taken in connection with the drawings will fully set forth the construction and advantages of the improvement to those skilled in the art to which such inventions relate without further detailed description.

Having described the invention, I claim:

A shoe having an insole whose outer edge is straight from the portion thereof on which the base of the little toe of the wearer's foot rests to the extreme outer edge of the heel portion of the wearer's foot that rests on the insole, and a rigid cuboid support lasted in the shank of said shoe to receive thereon the direct pressure of the cuboid bone and the muscles that hold said bone in place and to exert a greater pressure thereagainst than is exerted thereby against any other part of the arch of the foot.

In testimony whereof I affix my signature.

WILLIAM C. BURNS.
